Primary Examiner — Ian Simmons*Assistant Examiner* — E H Aldridge(74) *Attorney, Agent, or Firm* — Drinker Biddle & Reath LLP(57) **CLAIM**

The ornamental design for a hooded garment, as shown and described.

DESCRIPTION

FIG. 1 is a front elevated view of a hooded garment with the hood in the up position showing our new design;

FIG. 2 is a rear elevated view thereof;

FIG. 3 is a left side elevated view thereof;

FIG. 4 is a right side elevated view thereof;

FIG. 5 is a front elevated view of the hooded garment with the hood in the down position;

FIG. 6 is a rear elevated view thereof;

FIG. 7 is a left side elevated view thereof; and,

FIG. 8 is a right side elevated view thereof.

The broken lines in the figures disclose the environment related to the claimed design and do not form a part of the claimed design. The hatching in the figures is intended to show the character and contour of the surfaces and is not a feature or surface treatment of the claimed design.
